UNITED STATES PATENT OFFICE.

WILLIAM KEIL, OF NEW YORK, N. Y., ASSIGNOR TO L. DRYFOOS & CO., OF SAME PLACE.

DESIGN FOR FABRIC.

SPECIFICATION forming part of Design No. 29,461, dated October 4, 1898.

Application filed August 31, 1898. Serial No. 689,959. Term of patent 14 years.

To all whom it may concern:

Be it known that I, WILLIAM KEIL, a citizen of the United States, residing at the city of New York, borough of Manhattan, in the county of New York and State of New York, have invented and produced a new and original Design for a Fabric, of which the following is a specification, reference being had to the accompanying drawing, forming a part thereof, in which is represented a plan view of a section of fabric embodying the features of my design.

The design consists of a body A and border B. The body A presents alternate checkered and foliated stripes a and a' . The border B is separated from the body by an ornamental bar a^2 , and said border is decorated with foliate cruciform figures b , alternating with

spire foliate figures b' . The border is further decorated with a skirting b^2 , that presents festoon-connected foliate pieces. 20

The leading features of the design consist in a striped body, a border decorated with foliate figures, and a foliate skirting for the border. 25

I claim—

1. In a fabric, the design for the body A herein shown and described.
2. In a fabric, the design for the border B herein shown and described. 30
3. The design for a fabric herein shown and described.

WILLIAM KEIL.
